UNITED STATES PATENT OFFICE.

CHARLES H. IRWIN, OF WILMINGTON, OHIO, ASSIGNOR TO THE IRWIN AUGER BIT COMPANY, OF SAME PLACE.

DIE FOR MAKING AUGER-BITS.

SPECIFICATION forming part of Letters Patent No. 378,251, dated February 21, 1888.

Application filed October 15, 1887. Serial No. 252,415. (No model.)

To all whom it may concern:

Be it known that I, CHARLES H. IRWIN, a citizen of the United States, and a resident of Wilmington, Clinton county, and State of Ohio, have invented certain new and useful 5 Improvements in Dies for Making Auger-Bits, of which the following is a specification.

My invention belongs to that class of dies in the art of manufacturing auger-bits known as 10 "heading-dies."

The object of these dies is to form the head or cutting-point of the auger-bit. When the forging has passed under the operation of these dies, it is complete and ready to be "finished 15 up."

These dies are preferably used in making the solid center-stem auger-bit shown and described in Letters Patent No. 306,907, of October 21, 1884, and Letters Patent No. 361,522, 20 of April 19, 1887.

In the accompanying drawings, forming part 25 of this specification, Figure 1 is a view of the face of the lower die, which receives the forging shown in Fig. 5. Fig. 2 is a view of the face of the upper die used in connection with the die shown in Fig. 1. Fig. 3 is a cross-section of the die shown in Fig. 2, taken at the dotted line *x* *x*. Fig. 4 is a cross-section of the die shown in Fig. 1, taken at the dotted 30 line *xx*. Fig. 5 is a view of the forging as it appears when it leaves the trip-hammer and forming-dies. Fig. 6 is a view of the forging as it appears when it leaves the dies shown in Figs. 1 and 2. Fig. 7 is a view of the forging as it 35 appears after the surplus metal has been punched off the "flat head" shown in Fig. 6. Fig. 8 is a view of the face of one of the dies which hold the forging shown in Fig. 7, and Fig. 9 a view of the other dies which hold the 40 said forging. Fig. 10 is a side view of the plunger die or former which is used in connection with the dies shown in Figs. 8 and 9. Fig. 11 is an end view of the plunger die or former. Fig. 12 is an end view of the plunger 45 die or former when used in heading "double-twist" auger-bits. Fig. 13 is a view of the finished forging. Fig. 14 is a longitudinal section of the die shown in Fig. 8, (as far as the dotted line shown in Fig. 8;) and Fig. 15 is a 50 longitudinal section of the die shown in Fig. 9,

(as far as the dotted line shown in said Fig. 9.)

When the forging has left the trip-hammer dies, it appears as shown in Fig. 5, having the head *a*. This surplus metal in the head *a* is left to form the cutting and gimlet points, &c., 55 of the bit.

The rough forging shown in Fig. 5 is taken and placed in the dies A and B, part of the solid center stem, *a'*, resting in the die A, and part of the last convolution *a''* resting in the 60 groove *a'*, which is cut obliquely across the face of the die A. In the die A is also cut the long groove *a³*. In the die A are also cut the depressions *b* and *b'*, the depression *b* to receive one-half of the metal which forms the 65 wing *b²*, and the depression *b'*, which is semi-circular in form, to receive all the surplus metal left when the wing *b²* and point *b³* are formed.

In the die B is cut the groove *b⁴* and the depression *b⁵*. The die B is also cut away at *d*, so as not to interfere with the part of the convoluted blade of the bit which rests in the depression *a'* in the die A. 70

The depression *b⁴* in the die B receives one- 75 half of the metal which forms the point *b³*, and the depression *b⁵* receives one-half of the metal which forms the wing *b²*.

The dies C and D have each cut in their faces 80 the grooves *d'*, which receive the solid center stem, *a'*, of the auger-bit. Cut obliquely across the faces of the dies C and D are the grooves *d²*. In these grooves *d²* fit the convolutions *a''* of the blade of the bit. Where these grooves *d²* meet the grooves *d'*, the grooves are of pec- 85 cular shape to properly receive the convoluted blade of the auger-bit. The dies C and D each also have cut out at their ends the large semicircular groove *d³*. In the face of the groove *d³* in the die C is cut the depression or 90 groove *d⁴*. This depression *d⁴* is of the peculiar shape of the part *d⁵* of the auger-bit from which the spur and cutting-edges are formed. 95

E represents the plunger-die, the point *e* of which fits in the space formed by the grooves *d³* when the dies C and D are brought together. In the face of this plunger-die or former E is cut the deep cone-shaped depression *e'*. This depression *e'* forms the tip *e²*, from which the gimlet-point of the bit is formed. The face of 100

this plunger-die E is cut away at e^2 to assist in forming one of the lips of the part d^5 .

In the plunger-die shown in Fig. 12, which is used in heading double-twist auger-bits, the 5 face of the plunger-die is also cut away at e^2 .

The dies are used as follows: The forging, as shown in Fig. 5, is taken and the end having the head a placed in the die A, part of the solid center stem, a' , resting in the groove a^2 , 10 and about one-half of a convolution, a^3 , resting in the recess a^4 , the head a resting in the die A, as shown in Fig. 1 by dotted lines. The die B then descends and the metal in the head a is forced into the grooves a^5 and b^4 , thus 15 forming the point b^3 , and into the depressions b and b^5 , forming the wing b^2 , and the surplus metal is forced into the semicircular groove b' , forming the flat head a^6 . The forging when it leaves the dies A and B resembles the form 20 shown in Fig. 6. The head of the bit is then placed under a punch and the surplus metal (shown on the forging in Fig. 6) punched off. When the forging leaves the punch, it appears as shown in Fig. 7. The forging, as shown in 25 Fig. 7, is then taken and placed in the dies C and D, the solid center stem, a' , fitting in the grooves d' in said dies, and the convolutions fitting in the grooves d^2 , one-half in each die. When these dies are brought together, the two 30 grooves d^3 form a circular depression. The plunger-die is brought down into this depression, and the metal in the wing b^2 is forced up into the cavity e' , forming the point e^2 , (from which the gimlet-point of the auger-bit is 35 formed,) and forces the metal down into the peculiarly-shaped groove d^4 , so as to form, in connection with the plunger-die E, the part d^5 of the auger-bit. From this point d^5 are

formed the spur and cutting-edges of the auger-bit. If there remain any surplus metal, it will 40 form a thin crust around the sides of the plunger-die E, and can easily be removed. When I head double-twist auger-bits, I employ a plunger-die similar to the one shown in Fig. 12. When desired, the grooves d' and d^2 may 45 be omitted, and one continuous groove in which the auger-bit can rest may be employed, the peculiar depression d^4 , however, being present.

What I claim as new and of my invention, and desire to secure by Letters Patent, is— 50

1. In dies for heading auger-bits, the die A, having the grooves a^2 , a^4 , a^5 , and b' and the depression b , in combination with the die B, having the grooves b^4 and depression b^5 , substantially as set forth. 55

2. In dies for heading auger-bits, the dies C and D, having the grooves d' and d^2 and the large grooves d^3 , the die C having the peculiarly-shaped depression d^4 , in combination with a suitable plunger-die, substantially as set forth. 60

3. In dies for heading auger-bits, the dies C and D, having the grooves d' and d^2 and the large grooves d^3 , the die C having the peculiarly-shaped depression d^4 , in combination with the plunger-die E, having the cone-shaped 65 cavity e' and the cut-away portion e^2 , substantially as set forth.

4. In dies for heading auger-bits, the dies C and D, the dies C having the peculiarly-shaped groove or depression d^4 , in combination with 70 a suitable plunger-die, as E, substantially as set forth.

CHARLES H. IRWIN.
